PAINTER'S EASEL ATTACHMENT FOR
LADDERS

James L. Arnold, Oakland, Calif.

Application July 15, 1947, Serial No. 761,131

2 Claims. (Cl. 248—210)

1

This invention relates to improvements in easel attachments for ladders and particularly to an attachment which can be used with any conventional step ladder for convenient painting of window screens, sash, and the like, an attachment which is quickly and easily applied and removed at will and which is of minimum weight and bulk; one which will maintain its position and therefore positively support plane elements which are to be painted, washed, or otherwise treated.

This attachment cannot become accidentally dislocated or released though it can be readily removed at will when not supporting an object. It can also be used as a hanger for paint buckets, as a support for curtain rods and the like for painting or varnishing, and can be used as a hanger or support either in front or back of the ladder steps.

The objects and advantages of the invention are as follows:

First, to provide an easel attachment for step ladders and the like.

Second, to provide an easel attachment which securely maintains its position but which is easily applied and removed at will.

Third, to provide an easel attachment which locks in position on a ladder step when under load but which can be lifted off the step when the load is removed.

Fourth, to provide an easel attachment which can be mounted for support of elements either in front or back of the ladder steps at will.

Fifth, to provide an easel attachment which can be formed in pairs of individual units or in braced pairs, with the bracing either rigid or collapsible.

Sixth, to provide an easel attachment which is very light in weight and very economical to manufacture.

In describing the invention reference will be made to the accompanying drawings, in which:

Fig. 1 is a side elevation of the invention shown mounted on a step ladder.

Fig. 2 is a top plan view of one form of the invention shown applied to the steps of a step ladder, and drawn to an enlarged scale.

Fig. 3 is a side elevation of Fig. 2.

Fig. 4 is a front elevation of Fig. 2.

Fig. 5 is a side perspective view of the single element type of support.

Fig. 6 is a front elevation of a modified form of bracing which permits collapse of the easel attachment.

Fig. 7 is an enlarged fragmentary front view of the engaging slot for the collapsible bracing.

2

Fig. 8 is a side sectional elevation of Fig. 7 with one end of the bracing and the latching means added.

In its simplest form the invention consists of a double hook member formed from a flat bar 10 which terminates at one end in a dependent hook 11 to clip over the back edge of a ladder step 12 and being bent down at 13 and with the depending leg 14 terminating at its lower end in a hook 15 the back of which rests against the next lower step 16 of the ladder and which permits the use of very light-weight material for its construction because this lower hook has this support against the step. This describes the invention in its simplest form, two of these hooks being used and being mounted at opposite ends of the same step, and thus transforming the step ladder 17 into an easel, so that window sash or screens 18 may be supported in a slightly inclined position for washing or painting. This same unit can be used for artistic work such as oil painting.

In the preferred form the two elements are made into a unit with crossbracing, one strap 19 spanning the step engaging hook so as to rest against the back of the step, and the other strap 20 spanning the lower ends of the depending portions, to form a rigid structure; this type of bracing being adaptable to the rectangular type of construction shown in Fig. 6, or to the divergent type shown in Figs. 2, 3 and 4, this divergent type being similar except that the step engaging end is made relatively narrow, with the straps diverging from the rear hook to the easel hook 15, permitting, if desired, an easel support considerably wider than the ladder step.

Figs. 6, 7 and 8 show the collapsible type of bracing which consists of a cross brace two legs of which are pivoted to the respective easel members as indicated at 21 and 22 close to the dependent hooks, the two cross-members being intermediately pivoted together as indicated at 23, and the upper legs having each an anchor pivot respectively 24 and 25 having an enlarged head 26; the easel members each having a slot 27 enlarged at 28 to pass the head 26, and entering from the top at the bend 13, and each of the slots 27 terminating at the lower end in a lateral locking recess 29.

This brace is unlocked by drawing the two upper legs 30 and 31 toward each other which draws the pivots out of the lateral recesses 29 then moves the pivots up out of the slots, after which the unit can be collapsed to take up only about as much room as the easel members without the bracing.

For use, two of the hooks, Fig. 5, are hooked over the back at opposite ends of one step of the ladder and the lower end is then lowered to rest against the next step below. Thus the attachments are locked in place with the lower ends firmly supported against downward and rearward pressure. Window screens, sash, boards, and the like can then be supported and retained by the hooks 15.

The bracketed type is merely hung over the step and the forward end lowered so that the hooks 15 are supported by the next lower step against rearward thrust, while the collapsible type with collapsible bracing is merely expanded, the anchor pivots 24 and 25 are entered into the upper ends of the slots 27, then further expanded until the anchor pivots enter the lateral locking recesses, thus locking the attachment into a unitary rigid structure to be hooked over one step with the hooks 15 supported against rearward thrust by the next lower step.

Because of the form of the hook, and the drop member 14 engaging the front of the step, these attachments can be mounted at the rear of the steps for supporting paint pails and the like. It will be noted that it would be impossible for the attachment to become accidentally released because the step is gripped between the hook 11 which engages the underside of the step, and the dependent leg 14 at the bend point 13.

I claim:

1. An easel attachment for ladders having steps, comprising; two members each comprising a flat bar bent into a hook at one end to engage the underside and back of a step, and intermediately

bent down to engage the front of the step and with the bent down portion terminating in a supporting hook at a distance equal to the spanning distance across two steps of the ladder for support of the dependent hook against rearward thrust, and bracing for coupling the two members together to provide a unitary structure and comprising cross-bracing collapsible and expandible at will and including two members intermediately 5 pivoted together and forming four legs, with two of said legs pivoted to the lower ends of the respective bent-down portions and the other legs including means releasably engageable with means at the upper ends of said bent-down portions.

2. A structure as defined in claim 1; said other legs including each a fixed pivot having a head and forming the means releasably engageable, and the upper portions of said bent-down portions each having a slot terminating in a locking recess for reception and locking of said fixed pivots to lock the cross-bracing in position and forming said means at the upper ends of said bent-down portions.

JAMES L. ARNOLD.
